[57] CLAIM

The ornamental design for a stabilizer for heart bypass surgical procedures, as shown and described.

DESCRIPTION

FIG. 1 is an isometric view of a stabilizer for heart bypass surgical procedures showing our new design.

FIG. 2 is a front view thereof.

FIG. 3 is a left side view thereof.

FIG. 4 is a rear view thereof.

FIG. 5 is a right side view thereof.

FIG. 6 is a top view thereof.

FIG. 7 is a bottom view showing a first surface configuration thereof.

FIG. 8 is a bottom view thereof showing a second surface configuration.

FIG. 9 is a bottom view thereof showing a third surface configuration; and,

FIG. 10 is a bottom view thereof showing a fourth surface configuration thereof.
